UNITED STATES PATENT OFFICE.

EDGAR B. SYMONS, OF MILWAUKEE, WISCONSIN, ASSIGNOR TO SMITH AND POST COMPANY, OF MILWAUKEE, WISCONSIN, A CORPORATION OF WISCONSIN.

CRUSHING MACHINE.

1,005,358.

Specification of Letters Patent. Patented Oct. 10, 1911.

Application filed November 8, 1906. Serial No. 342,443.

To all whom it may concern:

Be it known that I, EDGAR B. SYMONS, residing at Milwaukee, in the county of Milwaukee and State of Wisconsin, have invented a new and useful Crushing-Machine, of which the following is a specification.

My invention relates to that class of crushing machines, having an outer bowl-shaped frame or shell, inside of which is an oscillating crushing-head surrounding a centrally located shaft.

The objects of my invention are, 1st; to so arrange the supports and bearings of the central shaft as to exclude dust therefrom, and 15 reduce friction; 2nd, to improve the means for lubrication; 3rd, to improve the manner of supporting and adjusting the crushing head; and 4th, to construct a simple and efficient machine, having its parts of wear easily replaceable.

My invention consists of the novel construction, arrangement, and combinations embodied in the machine herein fully shown and described, reference being had to the accompanying drawings which form a part hereof, and in which—

Figure 1 is a plan view of my machine having the dome cap removed and a portion of the crown-piece and frame broken away 30 to show the oiling device. Fig. 2 is a sectional elevation. Fig. 3 is a detail plan of the lower support of the crushing-head and adjusting wrench, showing parts of the upper adjusting ring and of the wrench broken away. Fig. 4 is a front elevation of parts detailed in Fig. 3, (the wrench removed) showing the upper ring in section and with part of the lower ring broken away to show the spirally threaded engagement of said two 35 rings. Fig. 5 is a left side elevation taken from Fig. 3, the wrench being removed. Fig. 6 is a plan view of the sleeve surrounding the central shaft immediately below the crown-piece showing the oil passages provided in said sleeve. Fig. 7 is a detail plan of the like roller collars provided in the upper and lower bearings of the main central shaft,—the upper ring of the roller cage in said view being broken away to show in section the bars which separate the rolls, and which rigidly connect the upper and lower rings of said cage. Fig. 8 is a detail elevation of another and equivalent form of the eccentric device employed for oscillating the 55 crushing-head, together with portions of as-

sociated parts shown in section. Fig. 9 is a detail sectional plan taken on line A-B, Fig. 8.

Similar figures relate to similar parts throughout the several views.

1 is the outer shell or frame to which the spider-armed crown-piece 2, is fitted and securely bolted. The spider-armed bottom 3, is preferably cast as a part of said frame, although it may be made separately and fitted to the body of the shell after the manner of the crown-piece. The main central shaft 4, is surrounded by three roller collars, after the manner of roller bearings. The upper roller collar is contained within 70 the crown-piece 2, and comprises rolls 5, set loosely in the cage 6. The middle roller collar is substantially contained within the crushing-head 7, and comprises the rolls 8 set loosely in the roller-cage 9. And the 75 lower roller collar, comprising rolls 10, set within cage 11, is contained within spider-armed bottom 3, of the main frame.

12 is a dome dust cap, fitted over the oil receptacle formed by the casting 13, which is 80 fastened to the crown-piece and prevents an upward movement of the adjacent roller-collar and the shaft 4.

The sleeve 14, detailed in Fig. 6, loosely surrounds shaft 4, is carried upon the roller-cage 9, and supports the roller-cage 6 together with rolls 5. The roller-cage 9, adapted to hold the rolls 8 in proper alignment, is carried on the hub of the bevel gear wheel 15, which is keyed in the usual way to shaft 90 4, and which has a lower end bearing on the inner leg of the angle-ring 16, supported by and bolted to the spider-armed bottom 3. The outer angle-ring, or adjusting ring 17, is held by its spiral tongue-and-groove, or 95 threaded engagement with the ring 16 (see Fig. 4) and in connection therewith protects gear-wheel 15, and affords a support to the crushing-head 7, which, in its oscillation, is free to slide upon ring 17. The hooked bar 18, pivotally connected to ring 16, at 19, may be made to engage with any one of the lugs 20, projecting from the ring 17, to hold the latter in desired position. The lugs 21, on ring 17, are made convenient for the application thereto of a wrench 22, used in turning said ring for vertical adjustment of the crushing-head. The stud-bolt, or pin, 23, projecting from the lower end of shaft 4, together with the wearing-plate 24, affords 110

a suitable end-bearing to sustain the weight of said shaft.

Recessed in crown-piece 2, are the holes 25, for receiving the adjusting bolts 26 which, in connection with the nuts 27, threaded thereon, and bearing against said crown-piece, serve to hold down the annular plate 28 and also the crushing head upon which said plate rests. The plate 28 is 10 movably fitted around the sleeve 14.

The dies, or concaves, 29, are removably secured in frame 1, opposite to the crushing-head 7, to form the crushing-hopper. The pinion 30, engaging with the bevel gear 15 wheel 15, for driving shaft 4, is preferably keyed to shaft 31, which is supported by its bearing 32, in frame 1. Shaft 31 is provided with the belt-wheel 33 secured thereto for the application of power.

20 That part of the main central shaft 4 which is substantially contained within the crushing-head as shown in Fig. 2, is preferably made eccentric to the center line of its end bearings, in which case the rolls 8 are 25 of like size. In the other and equivalent form of this eccentric device shown in Figs. 8 and 9, the main shaft 4 is made of uniform diameter throughout, and the rolls 8, are so graduated to suitable diameters as to 30 allow each of said rolls to maintain substantially continuous lines of contact both with shaft 4, and with the inner surface of the crushing-head 7, when the latter is eccentrically positioned with reference to said 35 shaft.

The wheel 34 supported by bearings 35, connected to the main frame, is driven in frictional contact with the shaft 31 and so operates through the common crank device 40 shown to drive the oil-pump 36 bolted to oil-tank 37. 38 is an oil-pipe connecting said pump with the oil receptacle in casting 13. 39 is a return oil pipe connecting the oil basin, provided in the bottom 3, with 45 said oil-tank.

In the operation of my crushing-machine the central shaft 4, is made to rotate through means provided therefor as shown and described. This rotation of shaft 4 causes the 50 rolls 8 to travel around said shaft and thereby impart to the crushing-head an oscillating or crushing movement whereby stone placed in the crushing-hopper is broken or crushed to sizes permitting it to fall through the discharge opening at the bottom of said 55 hopper. When it is desired to decrease the width of said discharge opening, the operator, by turning the nuts 27, lowers them to allow an upward movement of said crushing-head. The hook 18, being then disengaged, the crushing-head is raised by turning the ring 17 on its spiral support to the desired point of adjustment, when hook 18 is again engaged with one of the lugs 20. 60 During this operation the bolts 26 enter

farther into the recesses 25. The nuts 27 are then brought again in contact with the crown-piece.

Reversing the operation described increases the bottom opening of the crushing- 70 hopper allowing a coarser product.

Since provision for thorough and continuous lubrication is absolutely essential to the success of a machine of this type, an important feature of the roller collars surrounding shaft 4, is that they afford between the rolls passages or conduits, for the free circulation of oil, which passages I have arranged to make continuous along the entire length of shaft 4 by the peculiar construction of sleeve 14 as described and by opening free communications from both the middle and lower sets of rolls, into the cavity formed by the frame and angle-rings as shown in the drawing and as set forth. 75 This cavity constitutes a basin for the collection of oil and insures the lubrication of the gear-wheel and pinion. The circulation of oil through said conduits is effected by means of the oil-pump 36, driven as hereinbefore described, and which forces the oil from tank 37, upward through the pipe 38 into the receptacle in casting 13, whence by gravity the oil finds its way through passages indicated by the arrows (Fig. 2,) into 80 the chamber surrounding the pinion and thence through pipe 39, into tank 37.

Having thus described my invention, what I claim as new and desire to secure by Letters Patent is:

1. In a crushing machine the combination of an outer shell or frame with a crushing head, a support for said crushing head on which it slides, removably secured to the frame and a rotative shaft within the crusher 105 head and an eccentric device interposed between the shaft and the crusher head.

2. In a crushing machine, the combination of an outer shell or frame with a crusher head, a support for said crusher head, which 110 support together with the frame forms a liquid holding closed housing, a driving shaft in said housing and within the crusher head and driving gears within said housing.

3. In a crushing machine, in combination, 115 an outer shell or frame; a centrally located rotative shaft held in bearings connected with said frame; a crushing-head surrounding said shaft and mounted on an annular support secured to said frame; and a roller 120 collar interposed between said shaft and said crushing-head, said roller collar being adapted when said shaft rotates, to impart an oscillating movement to said crushing-head.

4. In a crushing machine, the combination 125 of a main frame, bearings in said frame, a main central shaft supported in said bearings, said bearings connected by passageways, a hollow head, a support therefor, a hollow liquid retaining part including the 130

- support and driving mechanism within said part, and an oil supply apparatus for circulating oil through such bearings, hollow head and part and passageways.
5. In a crushing machine, in combination, an outer shell or frame having a spider-armed bottom; a crown-piece secured to said frame; a centrally located shaft held by said crown-piece and said spider-armed bottom;
- 10 a hollow crushing head mounted on a support connected to said frame; a roller collar within said head and surrounding said shaft; and a sleeve surrounding said shaft between said crown-piece and said roller collar, said sleeve serving to prevent the upward movement of said roller collar, when said machine is in operation.
6. In a crushing machine, the combination of a main central crusher head and a driving shaft with a hollow liquid retaining inclosing housing completely surrounding said shaft for the exclusion of dust therefrom.
7. In a crushing machine, the combination of an outer shell or frame, a crown piece, a centrally located rotative shaft mounted in fixed bearings in said crown piece and frame, a hollow crushing head surrounding said shaft, a rotative device interposed between said shaft and said crusher head open at the top and bottom to afford oil passageways along said shaft.
8. In a crushing machine, the combination of an outer shell or frame, with a crown piece secured to said frame, a centrally located rotative shaft mounted in bearings in said crown piece and frame, a gear wheel secured to said shaft, a housing containing said gear wheel and a portion of the shaft and constituting an oil basin, and oil passages leading into and out of said basin.
9. In a crushing machine, in combination, an outer shell or frame; a centrally located rotative shaft provided with bearings supported in connection with said frame; a hollow crushing head, supported within said frame and surrounding said shaft; and means independent of said shaft for raising and lowering said crushing head. 45
10. In a crushing machine, in combination, an outer shell or frame; a centrally located shaft held in supports connected with said frame; a hollow crushing head surrounding said shaft; and an adjustable bottom support for said crushing head, said support comprising two angle-rings having 50 a spiral tongue-and-groove or threaded engagement with each other for raising and lowering said head.
11. In a crushing machine, the combination with a frame of a crusher head, a shaft, 60 a support on which the bottom of said crusher head stands and on which it is adapted to move and means for adjusting said support to raise and lower the crusher head.
12. In a crushing machine, the combination with a frame of a crusher head, a shaft, a support on which the bottom of said crusher head stands and on which it is adapted to move and means for adjusting said support to raise and lower the crusher head, 65 said means comprising two parts connected by a pin and a spiral adapted to be rotated with reference to each other.

In testimony whereof I affix my signature, in presence of two witnesses.
